UNITED STATES PATENT OFFICE

2,005,049

APPARATUS FOR MAKING IMITATION
ASTRAKHAN FUR

Georges Romane, St. Mande, France

Original application April 22, 1929, Serial No. 357,089. Divided and this application February 10, 1934, Serial No. 710,705. In France June 30, 1928

4 Claims. (Cl. 154—1)

In a prior Patent No. 1,731,591, granted October 15, 1929, I described artificial furs, especially imitation astrakhan, obtained by affixing "gibboushed chenille" on a packing made of tissue, fabric or other suitable material.

Chenille is a product consisting of a core made of any textile material, cotton for instance, around which are crosswise-arranged fibers, also made of any textile material, (silk, wool, etc.).

"Gibbousing" is an operation that consists in laying circularly the cross fibers of the chenille around their core by passing them through suitably heated revolving tubes.

The object of this invention is to construct a machine for making furs imitating natural astrakhan, according to the process described in my prior application No. 357,089, filed April 22, 1929, Patent No. 1,950,416, granted March 13, 1934, of which the present case is a division; such process consisting essentially in previously cutting up suitably gibboushed chenille or like material into bits of any desired shape and size, and in applying such bits on a backing made of fabric, hide or other material coated with a sticky coating such as, for instance, rubber cement, so that the said chenille bits may be positioned in any order and according to any arrangement which may be preferred, permitting an effect to be obtained which as nearly as possible resembles the natural fur.

The chenille employed may have been subjected to more or less marked gibbousing. Preferably, in order to obtain a final product offering closer resemblance to astrakhan, and, particularly to increase its strength, I start with a chenille having a section or width of 21 m. m. or more, previous to gibbousing, which section I reduce, by gibbousing, to 7 m. m., a ratio given mainly as an indication and variable according to the amount of curling imparted to the fibers by winding them more or less tightly around their core. When such winding extends beyond a complete circle formed by the fibers around their core, considerable advantage ensues over incomplete gibbousing.

In the accompanying drawings:

Figure 1 is a general side elevation of a machine for carrying out the invention;

Fig. 2 is an enlarged detail view of the chenille-cutting mechanism;

Fig. 3 is also an enlarged detail view, showing the driving and conveying device for the chenille bits, and their crowding and distribution, previous to final application, on a backing;

Fig. 4 is a detail view illustrating the gumming

device and the device for retouching the chenille bits on their backing before the latter is wound.

A machine constructed in accordance with my invention comprises essentially a frame 1, one of the ends of which carries the mechanism for cutting the chenille. Said mechanism is fitted with a conveyor band 2 running over a lower roll 3 and over two rolls 4 and 5. At 0 there is provided a cylinder permitting the chenille to pass between band 2 and a glass plate 1 which will be herein- 10 after described.

Said conveyor band 2 is driven by one of the rolls 3, 4 or 5 which is rotated by any suitable transmission means. Above and at each side of band 2 are positioned adjustably spaced plates 6 15 on which rests the glass plate 1 held, for instance by a cross-strap 8.

Said conveyor band 2 is combined with a second conveyor band 9 that passes over rolls 10 and 11 carried by frame 1. This band 9 is covered, for a distance $a-b$, by the glass plate 1 and, together with said plate, by a heating surface 12, held by another cross-strap 13. Said band 9 is driven, for instance, by means of a pulley 14, at a speed lower than the traveling speed 20 of band 2.

In front of the second band 9 there is located a circular blade 15 rotated by a suitable motor (not shown), which blade is designed to slit the chenille as will be hereinafter explained. 30

Below said blade is located a chute 16 leading to a revolving drum 17, the wall 18 of which is perforated. In front of the above described system extends another conveyor band 19, running over two rollers 20 and 21, and kept under proper tension by means of a suitable device 22. Motion is imparted to this band 19 by roller 20 itself driven by a belt transmission 23. On the side opposite the driving roller 20 there is provided, above band 19, a pressure roller 24 the ends 35 of which freely rest in suitable bearings 25 (Figure 3) carried by frame 1. Band 19, like the conveyor bands of the cutting mechanism, is covered along its sides by guiding members 6. Immediately in front of roller 24 there is arranged and 40 held by a clamp or cross-strap 26 a plate 1' made of glass or of any other transparent material. Said plate 1' also covers along the whole width thereof, another conveyor band 28 which runs over a roller 27 parallel with roller 21 and 45 somewhat spaced therefrom. Said band 28 is provided, like the foregoing one, with guiding members 6 and it runs over a second roller 29 and over a tensioning roller 30 (Figure 1). Rollers 21 and 27 are mounted on supports 31 and 50 55

32 adjustable vertically with respect to the frame by any suitable means as, for instance, by wing nuts 33.

Said band 28 is driven along by the aforesaid 5 roller 29, itself actuated by a belt drive 43.

The machine is completed by a device designed to permit of developing the backing whereon the bits of chenille are to be applied. Said backing, made of tissue, fabric or other suitable material, is indicated at 34, and it may be located wherever convenient on the machine. It is guided by a series of rollers 35, then passes through a suitable gluing device 36 and next runs over a roll 37 whence it passes to roll 38.

15 From roll 38 it goes over another roll 39, the periphery of which is provided with paddles. Next, it passes through a suitably designed device the duty of which is to fill up with any powdered textile the gaps between the stuck-on chenille bits. Said powdering device, housed 20 within a casing 40, is composed of a drum 41 containing the aforesaid powder and having a perforated wall (not shown). Said drum is revolved by a suitable transmission 42 driven by pulley 43. On issuing from casing 40, backing 34 goes to a suitable winding device 45 revolved by a belt transmission 45' from pulley 43.

It should be noted that where it passes through casing 40 the backing 34 furnished with chenille 30 is subjected first to the action of a beater 46 which assists discharge of the powder on the sticky fabric ground between the chenille bits. Said backing next passes over another beater 47 intended to rid it of the excess powder which 35 it may have received. It should also be noted that, previous to entering the powdering chamber 40, said backing follows an inclined path which is clearly seen in Figures 1 and 4, and wherealong may be retouched by hand, if required, the arrangement of the chenille bits on the sticky surface which has not as yet become 40 dry.

A suction funnel 48 is provided so as to lead 45 out the objectionable fumes from the rubber cement used to coat the backing.

The operation of the machine is as follows:

The chenille 50 has one of its ends placed under roll 0 of the cutting or slitting mechanism. Pressure exerted by said roll 0 forces said end 50 into contact with conveyor band 2 which carries it under glass plate 1 whereby it is slightly compressed. It then comes into contact with the second conveyor band 9 which is moving along at a speed slower than the travelling speed of band 2. Due to this slowing down, the chenille forms a succession of bends or loops, and while in that condition it is carried along by the second conveyor band 9 under the heating surface 12, the heat from which acts on it 55 after it has left the cutting-up mechanism. It then comes into contact with blade 15 which cuts it up, the bits falling into chute 16 and thence into drum 17, 18. Said drum deposits the bits, rid of their impurities, on conveyor band 19, on 60 which they can then be properly distributed either by hand or mechanically over the whole surface of conveyor band 19, care being taken

to avoid overlapping. Once so arranged on conveyor band 19, said bits travel to cylinder 24 which forces them to pass under transparent plate 7 until they abut against band 28 which is running over cylinders 27 and 29 and is slightly higher than band 19. Conveyor band 28 is running at a speed slower than the traveling speed of band 19. Consequently, the chenille bits are crowded towards end 19' of band 19. Said bits, so crowded, come into contact with band 28 whereon they are automatically distributed in the proper manner. At 28' they meet the backing 34 which has been coated with glue at 36 and adhere thereto. Said backing, so treated, next travels along the above described path to reach the powdering chamber 40 and next the winding device 45. Retouching of the chenille bits is effected on the sloping portion previous to entering into chamber 40, as hereinbefore explained.

It should be noted that backing 34 and band 28 ought not be driven at the same speed. Said drive is obtained by means of a pinion 43' secured to the end of cylinder 29 of band 28 and in mesh with another pinion 43'' secured to cylinder 37 of said backing 34.

I wish it to be clearly understood that the above described embodiment is in no way limitative and that any constructional modifications and changes may be introduced without departing from the scope of my invention as claimed.

I claim as my invention:

1. Apparatus for making imitation astrakhan fur, comprising means for feeding a continuous strip of backing material and a strip of previously gibbous chenille toward each other in opposite directions; means for automatically coating with adhesive material a face of the backing material during its feed movement; mechanism for automatically cutting the chenille sheet into bits of suitable size and shape and depositing them upon the coated face of the backing strip; means for applying powder upon the said coated face of the backing strip to fill the interstices between adjacent chenille bits; and means for winding up the powdered backing strip.

2. Apparatus according to claim 1, in which the powdered means comprises a casing through which the coated backing strip is designed to travel, a rotary powdering drum in said casing and around which the backing strip travels, and devices operable on the powdered strip to remove the excess powder therefrom.

3. Apparatus according to claim 1, in which additional means are provided for curling the finished product after having been powdered.

4. Apparatus according to claim 1, in which the powdering means comprises a casing through which the coated backing strip is designed to travel, a rotary powdering drum in said casing and around which the backing strip travels, means for winding up the powdered strip, and means immediately adjacent the winding means for removing, by suction, any fumes which may arise from the adhesive during the winding operation.

GEORGES ROMANE.
